ALLEN A. HORTON, OF PLYMOUTH, MICHIGAN, ASSIGNOR TO BURROUGHS ADDING MACHINE COMPANY, OF DETROIT, MICHIGAN, A CORPORATION OF MICHIGAN

KEYBOARD FOR CALCULATING MACHINES

Original application filed January 29, 1926, Serial No. 84,616. Divided and this application filed August 6, 1926. Serial No. 127,511.

The invention relates to a keyboard for calculating machines.

The general object of the invention is to provide an improved keyboard construction, particularly one that is in the form of a compact, self-contained unit that may be quickly attached to and detached from a calculating machine.

A more particular object is to provide an improved construction for returning the keys to normal position after they have been depressed.

Other objects and advantages of the invention will hereinafter appear.

An embodiment of the invention is illustrated in the accompanying drawings in which:

Fig. 1 is a side elevation of the forward part of a calculating machine, showing the keyboard attached thereto.

Fig. 2 is a sectional view of the keyboard taken between two banks or rows of amount keys, showing a key depressed and before the handle has been pulled.

Fig. 3 is a horizontal section looking at the keyboard from the bottom.

Fig. 4 is a transverse section taken at right angles to the banks of amount keys.

Fig. 5 is a fragmentary side elevation and section of the forward part of the keyboard showing one of the banks of amount keys and associated parts after the handle has started forward.

Fig. 6 is a front end elevation of the keyboard showing only the first key in each of the banks of keys, the other parts being omitted for the sake of clearness.

Fig. 7 is a side elevation and section showing the control keys and the interlocking mechanism therefor.

Fig. 8 is a fragmentary section and elevation showing one of the control keys and the locking plates associated with it.

Fig. 9 is a fragmentary section illustrating the assembly connections of the keyboard frame.

The invention is illustrated in connection with a calculating machine of the type shown in my co-pending application, Serial No. 84,616, filed January 29, 1926, of which the

present application is a division. No attempt will be made to describe said machine in detail in this application as it is not essential to an understanding of the keyboard. Reference is made to said co-pending application for any features of the machine not herein described. In order to avoid the use of reference numerals of high order and in order that the reference numerals may be in logical sequence, a new set of reference numerals will be used in this application.

The keyboard frame comprises a top plate 20, and a bottom plate 21 which are spaced apart and secured to three vertical plates 22 (Fig. 4). As shown in Fig. 9 the lower edges of the vertical plates have projections 23 extending into slots in the lower plate 21, the corners of the projections being swaged out to bear against the lower face of the plate 21 to hold the vertical plates in position. The vertical plates are provided with rectangular openings 24 near their upper edges, which communicate with the edges by narrow slots 25. The upper edges of the vertical plates are also provided with projections 26 which extend into slots in the top plate 20. The top plate 20 is connected to the vertical plates by a means of nuts 27 mounted in the openings 24 and provided with grooves 28 across their upper faces into which the portions of the vertical plates constituting the upper edges of the openings 24 are adapted to be seated. In assembling the keyboard frame, the nuts 27 are slipped into the openings 24 and then raised so that the upper edges of the openings engage in the grooves 28 after which the sides of the openings in the vertical plates immediately below the nuts are struck out to form projections 29 which hold the nuts in place. The plate 20 is then placed on top of the vertical plates with the projections 26 fitted into the slots in the plate 20. Screws 30 are then screwed into the nuts 27, the heads of the screws projecting laterally over the plate 20 and holding it in place as illustrated in Fig. 4.

The vertical plates 22 are provided at their forward ends with downwardly extending projections 32 (Fig. 9) and at their rear ends with similar projections 33. The forward

projections 32 serve as bearings for a cross shaft 34 which is carried by the keyboard unit and upon which certain parts are mounted as will be hereinafter explained. The 5 rear projections are adapted to extend down on the outside of one of the side plates and on one side of one of the center plates of the calculating machine and are provided with openings to receive screws 35 as illustrated 10 in Fig. 1. The two right hand vertical plates 22 also have downwardly extending hooks 36 which are adapted to engage over headed studs 37 on the frame plate of the machine.

The keyboard may be removed as a unit by 15 simply withdrawing the screws 35 at the rear after which it may be shifted slightly rearwardly and raised off the machine. It may, of course, be mounted as a unit on the machine by reversing these operations. When 20 seated in position the parts carried by it operate with the other mechanism of the machine as hereinafter described.

The keyboard is provided with a plurality 25 of banks of amount keys 10 accompanied by a bank of control keys at the right hand side of the keyboard comprising an error key "E", a repeat key "R", a non-add key "N A", a total key "T" and a sub-total key "S T". One of the advantages of the keyboard is 30 that the amount keys and the control keys are of similar construction; they are mounted in the keyboard in the same way, and the control keys are all located in a group in a single bank at the right hand side of the keyboard where they may be conveniently manipulated.

The stem of each amount key comprises a flat plate 40 which slides vertically in transverse slots in the top and bottom keyboard 40 plates 20 and 21. Each stem has two long parallel vertical slots 41 (Fig. 4) above which are two shorter vertical slots 42. The key stems are guided in the keyboard frame by positioning plates 43 which extend 45 through the right hand vertical slots 41 as shown in Figs. 2 and 4. These plates are held firmly in position by a rod 44 (Fig. 2) which projects through each plate and through the fixed plates 22 of the keyboard frame. The positioning plates 43 have projections 45 (Fig. 2) contacting the lower side of the top plate 20 of the keyboard to prevent the plate coming in contact with slidable latching plates to be presently described. 50 The stems 46 of the control keys are similar to those of the amount keys, except that instead of having parallel vertical slots, the two parallel slots are merged into large vertical slots 47 and 48 as illustrated in Fig. 8, 60 with the exception of the error key which is not latched down, in order to accommodate additional locking plates hereinafter described. The control keys are limited in their movement and prevented from binding 65 in the frame by a plate 43 similar to the

plates for the amount keys and located at the left side of the slot 47.

It will be observed from Fig. 6 that the control keys and their associated parts are on the outside of the right hand vertical 70 frame plate 22 where they are easily accessible.

In order to latch the amount keys in depressed position slidable plates 50 are provided for each bank of keys which extend 75 through the left hand vertical slots 41 in the key stems of that bank. These plates are normally urged forward by springs 51 connected at one end to lateral projections 52 on the rear ends of the fixed plates 43 and at 80 their other ends to upwardly extending projections 53 on the sliding plates. The plates 50 have a series of upwardly extending projections 54 (Fig. 5) provided with beveled noses 55 adapted to be positioned in the vertical slots in the key stems. In the normal undepressed position of the keys the noses extend slightly into the upper ends of the left hand vertical slots in the key stems as shown in Fig. 2. When a key is depressed 85 to the position of one of the keys illustrated in Fig. 2 the portion of the key stem between the long and the short vertical slot cams the plate 50 rearwardly against the tension of its spring 51 after which it is again moved forwardly by its spring to a position in which the nose projects into the upper vertical slot in the stem. This latches the key in depressed position, but does not prevent depression of a second key until the handle has 90 started forward. Depression of a second key will release the first since the latch plate is moved to releasing position during depression of the second key.

The control keys are likewise latched in depressed position by a similar latching plate 50 illustrated in Figs. 1 and 8.

The latch plates 50 also function in connection with the zero stops and safety mechanism of the machine as follows:

Each plate 50 has a hook-shaped forward end 60 as illustrated in Fig. 1 which extends over a lateral lug 61 on a zero stop member 62 pivoted on the shaft 34. There is one of these zero stop members for each latch plate 115 and, with the exception of the member corresponding to the control bank of keys, each has a rearwardly extending zero stop arm 63 (Fig. 2) adapted to be positioned in front of its respective stop bar 233 to prevent the bar 120 from moving when no key has been depressed in the corresponding numeral key bank. Each of these zero stop members including that of the control bank also has a downwardly extending arm which is bifurcated to 125 form a front portion 64 and a rear portion 64' which straddle the shaft 65 supported by the links 66 pivoted on the shaft 34 as illustrated in Fig. 6. Inasmuch as the latch plates 50 are normally urged forward, the zero stops 130

are normally urged in a counter-clockwise direction to cause the forward portions 63 of the bifurcated ends of the zero stops to contact the shaft 65. The shaft 65 is urged rearwardly by a spring 67 but is normally blocked from movement as will be later explained.

When the machine is given a stroke of operation the cam 74 (Fig. 1) is rocked counter-clockwise from the position illustrated in Fig. 10 by the handle 70 or by a motor and is then returned to said position. This cam carries a stud 200 contacting the rear end of a plate 201 slidably guided in slots in the frame plates 202, its sliding movement being limited by the pin 203. The sliding plate is normally urged rearwardly by a spring 205 which also tends to draw the front end of the plate 201 upwardly but the latter movement is normally prevented by the contact of a projection 206 on the rear of the plate with one of the frame plates 202. The front end of this plate 201 is provided with an upper shoulder 207 and a lower shoulder 208 both of which 25 are adapted to contact a cam roller 209 carried by the shaft 65.

In the normal position of the parts illustrated in Fig. 1 the plate 201 is prevented from moving rearwardly by the roller stud 200 and from tilting upwardly by the projection 206 which engages the frame piece 202. The shaft 65 is blocked from moving rearwardly by the engagement of the roller 209 with the shoulder 207. During the forward 35 stroke of the machine the stud 200 moves away from the plate and the latter is thereupon moved rearwardly by the spring 205 which also rocks it clockwise about the stud 203, the sliding movement being limited by the stud 203 and the rocking movement by the engagement of a projection 213 on the end 40 of the plate with the roller 209.

The rearward movement of the plate 201 permits the shaft 65 to move rearwardly until 45 stopped by the upper face 68 of a limiting stop 69 which contacts the under side of the keyboard plate 21. The plate 201 continues slightly rearward to provide clearance for the shoulder 208 to get behind the roller 209. This permits the zero stop members 61 to rock 50 counter-clockwise under the action of springs 51 which urge the latch plates 50 forward.

In banks of amount keys where no key has been depressed the latch plates 50 are free to move forward until the forward portions 63 of their zero stop members 61 contact the shaft 65 which moves to its rear position when the handle is operated as just explained. Such movement of the plates moves the noses 55 through the lower long vertical slots in the key stems a sufficient distance to lock both the amount and the control keys against movement during operation of the machine—also in the numeral key banks, the zero stop members 61 move counter-clockwise sufficiently to

move the zero stop arms 63 in front of their differential stop bars 233 to prevent the bars and their associated actuator segments from moving, it being understood that the stop arm 63 is omitted from the control bank.

In banks of amount keys where a key has been depressed, the latch plates 50 can move forward slightly, but only a limited distance since the projections 54 on the plates contact the portion of the key stems between the upper and lower slots as will be clear from Fig. 2. The forward movement is sufficient to lock the keys in position but it is not sufficient to permit the zero stop arms 63 to be moved in front of their differential stop bars. Accordingly the stop bars for the banks of keys in which amount keys have been depressed are free to move.

When one of the amount keys is depressed, the rearward movement of its latching plate 50 moves its zero stop clockwise and when the latching plate again moves forward to latch the key in depressed position the zero stop moves back to normal position. If one of the keys should be stopped in partially depressed position, the latch plate cannot be moved forward because the nose 55 contacts the portion of the key stem between the top and bottom vertical slots. This prevents the zero stop from moving counter-clockwise and prevents the shaft 65 from moving rearwardly when the machine is operated. The blocking of the shaft 65 causes the operating mechanism to be automatically disconnected from the driving shaft through the medium of arm 193 (Fig. 2) as explained in my co-pending application. The latch plates 50 thus control the automatic disconnecting feature; they control the zero stops and they serve both as a latching and a locking means for 105 the keys.

During the return stroke of the machine the stud 200 on the cam 74 contacts the end of the plate 201 and moves it forward thereby causing it to move the shaft 65 forward, rock 110 the members 61 clockwise, and move the latching plates 50 rearward to release all the depressed keys. The shoulder 208 being farther forward than shoulder 207 causes the shaft 65 and associated parts to be moved beyond 115 their normal forward position so as to insure that the keys will be released. As the slide 201 reaches the end of its forward position the projection 206 contacts the frame member 202 and the slide is rocked counter-clockwise 120 about stud 203 thereby causing the shoulder 208 to move down past the roller 209 which then moves rearwardly into contact with shoulder 207 and allows the parts to assume their normal position.

When the keys are released they are returned to normal position by a simple, inexpensive, and easily accessible means illustrated in Figs. 1, 2 and 5. The lower ends of the key stems on the under side of the key- 125

board plate 21 are provided with holes 70 and extending through the holes of all the key stems of one bank of keys is a coil spring 71. This spring also extends through eyes which are pressed out from the bottom plate 21 of the keyboard between the openings for the key stems. A small rod 72 (Fig. 1) projects through the rearmost loops of all the springs and a smaller rod 73 projects through the foremost loops of the springs for the banks of amount keys. A separate fastening member 74 (Fig. 7) projects through the foremost loop of the spring for the control keys. The springs 71 tend to hold all the keys in normal elevated position in which position the lower ends of the left hand slots 41 in the amount keys and the lower ends of the slots 47 in the control keys engage the lower edges of the positioning plates 43. This prevents the keys from moving the latching plates 50 into contact with the upper keyboard plate 20 and insures freedom of movement for the sliding latch plates.

When a key in a particular bank is depressed the spring 71 for that bank is extended as illustrated in Figs. 2 and 5. The extension of this spring is sufficient to cause it to urge the depressed key upwardly and, when the key is released, the spring immediately moves it to its normal undepressed position. If, while one of the keys is depressed, another key in the same bank is depressed, the extension of the spring by the second key will place a slightly increased force on the first key tending to move it to its undepressed condition and since the depression of the second key moves the latch plate 50 to unlatched position the first key will be moved to undepressed condition when the second key is depressed, thereby providing what is called a flexible keyboard.

This construction for returning the keys is simple, easily accessible, and the number of parts is a minimum. It is not necessary to provide springs for each key as is frequently done. All the parts are on the bottom of the keyboard where they are easily accessible and it is a simple matter to remove any of the springs by simply removing one of the end rods which holds it in position. The use of eyes pressed out from the bottom plate also reduces the number of parts.

The lower ends of the key stems of the amount keys are adapted to contact differential stops 252 on the stop bars 233 as illustrated in Fig. 4. Since some of these stops are offset the keys are provided with cut away portions 75 so as to leave remaining portions which may be positioned to engage their respective stops and at the same time leave space to permit other stops to pass them.

Suitable interlocking mechanism is provided between the control keys to prevent depression of more than one control key at a time. This comprises a series of plates 80

(Figs. 1 and 7) mounted between the top and bottom plates 20 and 21 of the keyboard frame and in the slots 47 of the control keys. The forward plate has a slot 81, the rear end of which normally engages a projecting end of the rod 44 (Fig. 7). A limiting stud 83 fixed on the plate 43 projects behind the rear plate 80. The plates 80 have beveled portions for the key stems to strike and the limit of movement of the plates between the limiting studs is equal to the width of one key stem. When one of the control keys other than the error key is depressed, the part of the key stem above the slot 47 passes between the two adjacent plates 80 or in front of the foremost plate or back of the rearmost plate as the case may be, thus moving the plates together and preventing depression of another control key other than the error key as will be clearly understood from Fig. 7. It will be observed that the latch plate 50 (Fig. 1) will be actuated during depression of a key before the interlock operates. This means that if the control key is depressed, another may be depressed without operating the error key as is usually required. Depression of the control key releases the key already depressed but two control keys cannot be depressed at the same time. This gives a flexible bank of control keys and at the same time provides an interlock that prevents two control keys being depressed simultaneously.

The forward plate 81 also has a lateral lug 85 that prevents a subtraction lever (not shown) operating in slot 86 from moving to its proper position at the rear of the slot when one of the control keys is depressed.

The error key is employed to release any depressed amount or control key when the wrong key has been depressed. The locking plate 50 for the control keys has pivoted to it an arm 84, the upper forward end of which projects into a notch formed in the error key stem. When the error key is depressed it moves the locking plate 50 for the control keys rearwardly considerably further than when the plate is moved rearwardly on depression of one of the other control keys with the result that the corresponding member 61 is rocked clockwise sufficiently to force the shaft 65 forwardly and thereby move all of the other latch plates 50 rearwardly far enough to release any keys that may have been depressed.

Interlocking means is provided between the total and sub-total keys and the amount keys to prevent depression of the latter when a total or sub-total is being taken. For this purpose there is provided a cross slide 90 mounted in slots formed in the vertical keyboard plates 22. A spring 91 (Fig. 3) is mounted in a recess in the forward end of the slide and compressed between one end of the recess and the left hand plate 22. This spring normally urges the slide to the position illus-

trated in Fig. 3 so that slots 92 in the rear edge of the slide are normally opposite the noses 55 on the projections 54 of the locking plates 50. The plates 50 are thus free to move without interference from the cross slide when amounts are being entered in the machine with the total or sub-total keys in normal position. The right hand end of the slide 90 has an integral depending portion 10 93 which rests on the lower plate 21 of the keyboard and which has inwardly extending ears 94 and 95 projecting into recesses in the sides of the total and sub-total key stems respectively. The upper ends of the recesses 15 are inclined at 96 as illustrated in Fig. 4 so that when the total or sub-total key is depressed the slide 90 is moved to the right and the notches 92 are moved from in front of the noses on the latching plates 50 so that when 20 these plates move forward the noses strike the edge of the cross plate 90 instead of entering the notches.

Accordingly, when either the total or sub-total key is depressed and the machine is 25 operated the plates 50 move forward until their noses engage the edge of the slide 90 which movement is sufficient to position the plates to lock the keys against movement, but is not sufficient to permit the zero stops 30 61 to move the zero stop arms 63 in front of the stop bars. Since the cross bar 90 acts on all the latch plates 50 none of the zero stop arms can move to arresting position and hence all the stop bars are free to move, a 35 condition which is necessary in the taking of a total. The movement of the latching plates 50 is sufficient to move the members 61 so that they do not block the control rod 65 enough to cause the machine to be automatically disconnected.

It will thus be seen that there has been provided a simple, unitary keyboard construction that may be readily attached to and detached from a calculating machine. In addition to carrying the keys and associated locking parts and mechanisms, the keyboard carries the zero stops for the differential mechanism. The latch plates for latching the keys in depressed position also act as locking plates and they further act to move the zero stops to control the differential mechanism as well as to control the safety disconnecting feature. When the keyboard 50 is placed in position the zero stops are positioned relative to the stop bars and the slide 201 so as to be in operative relation to them and the keys are in position for their stems to act as stops for the differential stop bars.

60 It is to be understood that the structure shown is for purposes of illustration only and that variations may be made in it without departing from the spirit and scope of the invention as defined by the appended 65 claims.

I claim:

1. A calculating machine keyboard having a plurality of banks of keys, a latching plate for each bank, a cross shaft, a plurality of zero stop members pivoted to the cross shaft, and a control rod pivoted to swing about the cross shaft, one end of each zero stop being connected to its respective latching plate to move in both directions with it and the other end having spaced arms straddling the control rod. 70

2. A calculating machine keyboard section having a plurality of banks of depressible keys, a latching plate for each bank, each latching plate controlling a zero stop member carried by the keyboard, means for urging the latching plate in a direction to cause the zero stop members to move to arresting position, and a control rod carried by the keyboard for normally holding all of the 80 said zero stop members out of arresting position. 85

3. A calculating machine keyboard section having a plurality of banks of depressible keys, a latching plate for each bank, a pivoted zero stop member connected to each latching plate, each of said zero stop members having a bifurcated end, and a control rod carried by the keyboard and positioned in the 90 slots in the ends of the zero stop members, the diameter of said control rod being less than the width of said slots. 95

4. A calculating machine keyboard having a plurality of banks of depressible amount keys, a latch plate for each bank, a zero stop member controlled by each latch plate, a control rod carried by the keyboard for controlling the operation of the zero stop members and latch plates, an error key having a latch plate and a member associated 100 with the control rod similar to said zero stop members, connections between the error key and its latch plate for causing depression of the error key to move its latch plate to actuate the control rod to release the latches for 105 the banks of amount keys. 110

5. A calculating machine keyboard having spaced top and bottom plates, banks of depressible keys having stems extending through both plates and slidably mounted 115 therein, each of said stems being provided with two spaced parallel slots, stationary guide plates for each bank of keys positioned between the top and bottom plates, each guide plate extending through one set of slots in the key stems of its bank to guide the keys and being provided with portions which hold the top and bottom plates in spaced relation, and slidable key latching plates extending through the other set of 120 slots in the stems of each key bank. 125

6. A calculating machine keyboard having spaced top and bottom plates, banks of depressible keys having stems extending through both plates and slidably mounted 130

therein, each stem having two sets of slots therein, means for urging the keys upward to normal undepressed position, guide plates for each bank of keys positioned between 5 the top and bottom plates, each guide plate extending through one set of slots in the key stems of its bank to guide the keys and to limit their upward movement, said guide plates being provided with portions for 10 holding the top and bottom plates in spaced relation, and key latching plates positioned between the top and bottom plates, each of said latching plates being slidably mounted in the other set of slots in the key stems of 15 its bank.

7. A calculating machine keyboard having banks of depressible keys, a latching plate for each bank movable forward and backward, a zero stop member for each latching 20 plate, and a common control rod for said zero stops, each zero stop member being connected to its latch plate to move in both directions with said plate to enable the control rod to control the latches in both directions of their 25 movement.

8. A calculating machine keyboard having banks of depressible keys, latch plates for latching said keys in depressed position, zero stop members connected to said latch plates 30 to move with them, an error key, and mechanism operatively connecting the error key with the zero stop members whereby depression of said error key will move said zero stop members to move said latch plates to 35 release depressed keys.

9. A calculating machine keyboard having banks of depressible keys, latch plates for latching said keys in depressed position, zero stop members connected to said latch plates 40 to move with them, a control rod for controlling said zero stop members, an error key, and connections between said error key and said control rod for moving the control rod when the error key is depressed to thereby 45 move the zero stop members to move the latch plates to release depressed keys.

10. A calculating machine keyboard having a plurality of banks of depressible amount keys, each bank having a latch plate 50 for latching its keys in depressed position, a zero stop member for each latch plate, said zero stop being normally out of arresting position, means for moving each latch plate to move its zero stop to arresting position when 55 no key in its bank is depressed, a total key, and means controlled by said total key when it is manipulated for limiting the movement of the latch plates of all the banks to thereby prevent the zero stops in all banks from moving 60 to arresting position.

11. A calculating machine keyboard having a plurality of banks of depressible amount keys, a latching and locking plate for each bank for latching and for locking its 65 keys in position, a zero stop member for

each latch plate, each latch plate being movable to one position to latch a depressed key of its bank in depressed position and to another position to lock all the keys of its bank, said plate acting when no key in its bank is depressed to move its zero stop to arresting position, a total key, and means set by depression of said total key for limiting the movement of the latch plates in all the banks to prevent their zero stops from moving to arresting position while still allowing the latch plates to move to key-locking 70 position.

12. A keyboard for calculating machines having banks of depressible amount keys, a latch plate for each bank for latching the keys of its bank in depressed position, each latch plate also being movable to a position to lock the keys of its bank against movement during operation of the machine, a zero 80 stop for each latch plate controlled in its movement to and from arresting position by its latch plate, and means controlling said zero stops to cause them to control the movement of their latches to key-locking position. 85

13. A keyboard unit for calculating machines comprising a structure, supporting rows of depressible keys, a plurality of latching plates for latching the keys in depressed position, a shaft mounted on one end of said structure, a plurality of zero stops pivoted on said shaft, said zero stops being connected to said latch plates to act to release said plates, and a rod pivotally supported by said keyboard and positioned to cooperate with 90 said zero stops to be controlled by them and to act on them to release the latch plates.

14. A keyboard for calculating machines having rows of depressible keys, a latch plate for each row, a pivoted zero stop member 105 connected to each latch plate, said zero stop members having relatively wide slots therein, and a control rod positioned in said slots, the diameter of said rod being less than the width of said slots.

15. A calculating machine keyboard having a plurality of banks of depressible amount keys, a zero stop member for each bank of keys, said zero stop members being normally out of arresting position, means for moving all of said zero stops to arresting position, and means operated by depression of each amount key for altering the movement of the zero stop of its bank toward arresting position by said moving means to thereby prevent said zero stop from reaching arresting 115 position.

16. In a calculating machine having an operating mechanism, banks of depressible amount keys, a latch plate for each bank of amount keys to latch the keys in depressed position, and depressible control keys; a zero stop controlled by each plate and normally in non-arresting position, means for moving the latch plates as the machine is operated 125 130

to move the zero stops to arresting position, and means set by depression of one of said control keys acting to arrest the latch plates as the machine is operated to thereby prevent the zero stops from reaching arresting position when the machine is operated with a control key depressed.

17. The combination in a calculating machine of a series of stop members released by 10 operation of the machine for movement against stops positioned by amount keys, a zero stop for each stop member normally positioned so as to permit movement of said member, and means actuated by operation of 15 the machine acting to move all the zero stops for members for which no key stops have been set to positions to prevent movement of their respective stop members.

18. In combination, in a calculating machine having banks of depressible keys and stop members released by operation of the machine for movement against stops set by depression of said keys; a latching and locking plate for the keys of each bank, means 25 urging said plates toward locking positions beyond their latching positions, a zero stop member connected to each plate, means for limiting the movement of said plates to retain them in latching position with the zero 30 stops out of position for arresting the stop bars, said last-named means acting automatically upon operation of the machine to release said latch plates for movement to locking position, said latch plates and keys having 35 cooperating portions which permit the latch plates in blanks in which no keys have been depressed to move to locking position such that their zero stops move to arresting position and which permit the latch plates in 40 banks in which a key has been depressed to move to locking position but which limit the movement of said plates in the latter banks to prevent the zero stops from reaching arresting position.

45 19. A calculating machine keyboard having a plurality of banks of depressible keys provided with key stems, a latching and locking plate for each bank extending through slots in the key stems of its bank and adapted 50 to occupy both a latching and a locking position relative to said key stems, means urging said plates toward their latching and locking positions, each plate having projections engageable by the key stems of its bank so 55 that, when a key in its bank is depressed, the plate for said bank is moved after which it automatically returns to normal position to latch the key depressed, control means normally holding said plates in latching condition, and means moving said control means 60 as the machine is operated to free said plates to enable them to move to locking position whereby the plates act to lock the keys in position.

65 20. In a calculating machine having an

operating mechanism, a keyboard having a plurality of banks of depressible keys, a latching device for each bank, a control rod for all of said latching devices pivoted to swing on said keyboard and adapted to be operated by said operating mechanism, and a pivoted zero stop member connected to each latching device, all of said zero stop members being associated with said control rod to control movements thereof and to be controlled by it.

In testimony whereof I have subscribed my name.

ALLEN A. HORTON.
